UNITED STATES PATENT OFFICE.

LAURENCE A. HAWKINS, OF SCHENECTADY, NEW YORK, ASSIGNOR TO
GENERAL ELECTRIC COMPANY, A CORPORATION OF NEW YORK.

BLOCK-SIGNAL SYSTEM.

No. 856,583.

Specification of Letters Patent.

Patented June 11, 1907.

Application filed November 8, 1906. Serial No. 342,455.

To all whom it may concern:

Be it known that I, LAURENCE A. HAWKINS, a citizen of the United States, residing at Schenectady, county of Schenectady, State of New York, have invented certain new and useful Improvements in Block-Signal Systems, of which the following is a specification.

My invention relates to block-signal systems for electrically operated roads, and its object is to provide a more efficient system than has been proposed heretofore.

In electrically-operated roads in which the rails must serve as return conductor for the power current, it has been proposed to separate the signal-blocks from each other by means of reactance bonds and similar devices, which prevent the flow of the alternating signal current from one block to another while permitting the power current to pass. Since these devices must carry the power current without saturation, they are large, expensive and inefficient. In order to improve the efficiency of such systems I have proposed heretofore an arrangement described in a former application, Serial No. 329,347, filed August 6, 1906, in which alternating-currents of different character and high frequency are employed for actuating the signal devices of adjacent blocks, so that the current in one block cannot affect the devices connected to the rails in the next block. With this arrangement, the rails may be conductively continuous for all currents, and the cost and waste of energy in inductive bonds and the like avoided.

The object of my present invention is to provide a system of still greater efficiency, and to secure this result I arrange the signal system so that all signal circuits are normally open, the signals operating on the normal danger plan, and provide means whereby, in spite of the continuity of the rails, a moving train is able to close a signal circuit in advance of it, so as to clear the signals in the proper order. With this system no power is employed in the signal circuits as long as no trains are running, and the amount of power consumed at any time is proportional to the number of trains; so that a great saving in power is secured.

My invention in one aspect, consists in the combination with electrically-operated roads having both rails conductively continuous

for all currents of normally open-circuited 55 transformers connected across the rails at intervals, with means controlled by a moving train for closing the circuit of a transformer ahead of the train, so as to operate the signal devices for the block which the train is about 60 to enter, and to clear the signal for that block if the block is clear.

My invention comprises a number of features which contribute to the efficiency and reliability of the system, and which will be 65 specifically pointed out in the appended claims.

My invention will best be understood by reference to the accompanying drawing, in which

Figure 1 shows diagrammatically a signal system arranged in accordance with my invention; and Fig. 2 shows a modification of the same adapted for the control of home and distant signals.

Referring first to Fig. 1, A represents the rails of an electric road, both of which are made conductively continuous, so as to serve as return conductor for the power current. B represents the third-rail, or other supply conductor, connected to one terminal of the power generator C, the other terminal of which may be connected to the rails A through the differential choke-coil c. This generator may furnish either direct current or low frequency alternating current. D represents a high-frequency alternating current generator, which furnishes the power for the signal circuits. E E' represent transformers, the primaries of which are connected to the transmission wires d, which extend from the generator D along the track, and the secondaries of which are connected across the rails through a small resistance e which may be employed to limit the flow of current from 95 the transformer when short-circuited by a train. The transformers E E' are normally open-circuited on either their primary or secondary side. I have shown the secondary open-circuited, but it will be understood that if the relative values of current and voltage make it preferable, the primary may be open-circuited instead. F F' represent track relays responsive only to alternating current if direct current is used for the power circuits, or to alternating current of a predetermined frequency only if alternating current is used for the power circuits. I

have illustrated a relay of the induction type having a short-circuited secondary member f carrying the relay contacts and two co-operating windings, one of which, f^1 , is connected across the track, and the other, f^2 , supplied from the line-wires d through any phase-controlling device, such as the condenser f^3 , arranged to give a phase-displacement between the currents in the two windings f^1 and f^2 . Any other suitable type of relay responsive to alternating current only, or to alternating current of one frequency only may be employed. G G' represent electromagnets controlling the circuits of 15 transformers E and E' and relays F and F' , respectively, by means of a normally open contact in series with the transformer and a normally closed contact in series with the relay. The electromagnets G G' are shown 20 supplied from batteries g , but any other suitable source of current may be employed for these magnets,—for instance, if the magnets are arranged to operate on alternating current, they may be supplied directly from 25 the transformers E E' . These magnets are normally deenergized. H H' represent signals provided with any suitable mechanisms indicated diagrammatically by the solenoids I I' . The signals are normally at danger, 30 with their operating mechanism normally deenergized. i represents any suitable source of current for the operating mechanism. J J' represent short insulated sections in one of the rails A . These sections may each be 35 a single rail-length, and are bridged by conductors j , so that the conductive continuity of the rail is preserved. The insulated section J serves to complete momentarily the circuit of the magnet G' . It performs the 40 function of a track instrument which might be substituted for it. The magnet G' , as will be hereinafter explained, when momentarily energized, closes a maintaining circuit for itself. In other words, it is what is known 45 in the art as a "stick-relay." k^1 , k^2 , and k^3 represent contacts controlled by the signals H H' . The operation of the system is as follows. Normally, all the signal circuits are open and no current is flowing in any of them. When 50 a train reaches an insulated section J , the axles of the train circuit connect the section to the opposite rail, thereby completing a circuit from the upper terminal of battery g through the magnet G' , the upper rail A , the 55 train-axles, and insulated section J to the lower terminal of the battery. The magnet G' , consequently, is momentarily energized and draws up its armatures. Let it be assumed that the right-hand magnet G has 60 been thus energized by a train approaching from the right. When it draws up its armatures a maintaining circuit for itself is closed from the upper terminal of battery g through the magnet winding G , and through its upper armature, and the contact k^2 , controlled 65 by the signal H to the lower terminal of battery g . Consequently, the magnet G does not drop its armatures when the train passes from the insulated section, but holds them closed. The raising of the lower armature 70 serves first to break the circuit of the track winding f^1 of relay F , and then to close the circuit of the transformer E . The purpose of closing the transformer circuit is to energize the relay F' for the block which the train is about to enter, while the opening of the track relay winding of F is to prevent its acting as a short-circuit for the transformer winding. When the transformer E is thus connected to the track, it supplies to the 75 track-rails a current which energizes the winding f^1 of the relay F' , if no rails are broken between the transformer and relay, and no train is in the track section between, so as to short-circuit the relay. This circuit 80 may be traced from the left hand terminal of the secondary of transformer E , through right-hand resistance e , lower rail A , left-hand resistance e' , winding f^1 of relay F' , contact k^3 of signal H' , back contact and 85 lower armature of magnet G' , upper rail A , lower armature and front contact of magnet G , to right hand secondary terminal. When the relay track winding is thus energized, a torque is produced on the secondary member 90 f , so that the relay contacts are closed, thereby energizing the operating mechanism I of the signal H , which is consequently drawn to clear position to indicate to the approaching train that the block is clear. 95

It will be seen that the transformer is at the entrance-end of the block and the relay at the exit end. There are two reasons for this arrangement: First, the circuits of the magnet G and its armatures are made shorter 100 and simpler, and second, the point at which the relay F' is short-circuited by an approaching train is made more definite, as will be shortly explained. When the signal H clears, it first closes a second circuit for the transformer E through the contact k^1 and then breaks the circuit of track-winding f^1 of relay F at contact k^3 and the maintaining circuit of magnet G at contact k^3 . Magnet G is, 105 consequently, deenergized and drops its armatures, but the circuit of the transformer E is still closed and the circuit of relay winding f^1 is still open at the contacts of the signal. These conditions are maintained, and the signal remains at clear position, until the 110 train approaches so close to the transformer as to pull down the voltage supplied to the track an amount sufficient to cause the left hand relay F' to drop its armature. This will occur when the train reaches a point a 115 certain distance from transformer E determined by the frequency of the transformer current, the regulation of the transformer, and the design of relay F' . By employing a high frequency for the signal currents, to 120

which the rails offer a high impedance, and by properly designing the transformer and the relay, this distance may be made one hundred feet, or even less. One reason for placing the transformer at the entrance of the block is to make this distance determinate. If the relay were placed at the entrance-end of the block, the distance at which the train would shunt the relay would be greater, and consequently more liable to variation.

When the signal goes to danger, due to the near approach of the train to the transformer E, the contacts controlled by the signal break the transformer circuit and close the circuit of winding f' of relay F, thereby restoring all the circuits to their original condition, with no current flowing in any of them. Thus, it will be seen that no current at all is employed in any of the signal circuits as long as no train is running, and for each train a certain amount of current is employed while the train is running from an insulated section J to the succeeding transformer.

If the movement of the signal were relied upon entirely for breaking the maintaining circuit of the magnet G, it is obvious that a failure of the signal mechanism or a sticking of the signal at danger, would leave magnet G energized, which would prevent the signal in the rear from clearing. Consequently, I prefer to arrange the circuit of the magnet G so that when the train enters the succeeding block the magnet will be positively short-circuited. If the insulated section J that energizes the stick-relay G' ahead, is near the entrance of a block, that same section may be used to short-circuit the stick-relay G behind, as shown in Fig. 1. If it is not near the entrance of a block, another short insulated section may be employed for this purpose; or if the magnet G is supplied from the circuit of the transformer E, it will be short-circuited without the use of any special connections whatever when the train short-circuits the transformer in passing it.

In Fig. 1 I have shown home signals only, in order to simplify the drawing. If it is desired to give caution indications, as well as clear and danger, the result may be secured in a number of ways. For instance; if the system is applied to a road having long blocks, where it is desired to place the distant signal at some point near the center of the block to give indication of the condition of the following home signal, no change whatever need be made in the circuit-connections shown in Fig. 1, except to provide contacts on the home signal for controlling the distant signal in the usual manner, so that the distant signal clears and goes to danger when the home signal does. The insulated section J would, of course, be placed back of the distant signal far enough to allow

the distant signal to clear before the train reaches it.

In the case of short blocks, where it is desired to place the distant signal for one block at the entrance of the preceding block, the desired indications may be obtained in a simple manner by designing the transformer and relays so that when a transformer has its circuit closed it will energize two relays ahead. This arrangement is shown in Fig. 2. The only changes in this figure are the addition of contacts on each home signal controlling the distant signal in the rear, and the omission of the signal-controlled contacts for controlling the stick-relay G. In Fig. 2 the magnet G has its maintaining circuit broken solely by the train reaching the succeeding insulated section J and short-circuiting the magnet winding as in Fig. 1, and maintains its armatures in raised position until the train reaches this section. The only disadvantage resulting from the omission of the signal-controlled contacts shown in Fig. 1, is that a larger current is drawn from the transformer, since the transformer circuit remains closed until the train is directly over it.

The operation of the signals shown in Fig. 2 will be evident from the drawing and from what has been said in describing Fig. 1. Each transformer is arranged to impress a sufficiently high voltage on the rails to energize two relays ahead, so that when the transformer E has its circuit closed both the relay F and the relay beyond it, not shown on the drawing, will be energized so as to close the circuits of both home signals H and H'. The clearing of the two home signals closes the circuit of the distant signal L through the contacts k of the two home signals in series, so that a train approaching the signals H and L will find both of them cleared if both blocks ahead are clear. If only one block ahead is clear, the home signal H alone will have cleared, since, in that case, the signal H' will not have cleared so that the circuit of the distant signal L will be open. Of course, if the block directly ahead is occupied, neither of the signals H and L will be cleared.

While in Fig. 2 I have shown two separate arms for giving the danger, caution and clear positions, it will be understood that a single three-position arm may be employed if desired.

I do not desire to limit myself to the particular construction and arrangement of parts here shown, but aim in the appended claims to cover all modifications which are within the scope of my invention.

What I claim as new and desire to secure by Letters Patent of the United States, is:

1. In combination with an electrically-operated road having both rails conductively continuous for all currents, normally open-circuited transformers adapted to impress an alternating voltage on the rails.

- means controlled by a moving train for closing the circuit of a transformer ahead of the train, and signal controlling means responsive to the voltage impressed on the rails by the transformers.
2. In combination with an electrically-operated road having both rails conductively continuous for all currents, transformers and signal-controlling relays connected at intervals to the rails, said transformers being normally open-circuited, and means controlled by a moving train for closing the circuit of a transformer ahead of the train.
15. 3. In combination with an electrically-operated road having both rails conductively continuous for all currents, transformers and signal-controlling relays connected to the rails, and normally open switch contacts in circuit with said transformers arranged to be closed by an approaching train.
25. 4. In combination with an electrically-operated road having both rails conductively-continuous for all currents, normally open-circuited transformers connected at intervals across the rails, means controlled by a moving train for closing the circuit of a transformer ahead of the train, a relay responsive to alternating-current connected to the rails ahead of the transformer, and a signal controlled by said relay guarding the portion of track between said transformer and relay.
35. 5. In combination with an electrically-operated road having both rails conductively continuous for all currents normally open-circuited transformers connected at intervals across the rails, relays having normally closed connections to the rails at intervals and responsive to alternating-current, and means controlled by a moving train for closing the circuit of a transformer ahead of the train and opening the circuit of an adjacent relay.
45. 6. In combination with an electrically-operated road having both rails conductively continuous for all currents, transformers connected at intervals across the rails, normally open contacts in series with said transformers, means operated by an approaching train for closing one of said contacts and connections whereby said contact is opened when the train enters the succeeding block.
55. 7. In combination with an electrically-operated road having both rails conductively continuous for all currents, transformers connected at intervals across the rails, normally open contacts in series with said transformers, electro-magnets for closing said contacts, connections whereby a magnet is energized by an approaching train, and connections whereby said magnet is deenergized when the train enters the succeeding block.
60. 8. In combination with an electrically-operated road having both rails conductively continuous for all currents, transformers con-
- nected at intervals across the rails, normally open contacts in series with said transformers, electro-magnets for closing said contacts, connections whereby an electro-magnet is momentarily energized by an approaching train, a maintaining circuit for the electro-magnet arranged to be closed when the electro-magnet is energized, and connections whereby the electro-magnet is deenergized when the train enters the succeeding block.
70. 9. In combination with an electrically-operated road having both rails conductively continuous for all currents, transformers connected at intervals across the rails, normally open contacts in series with said transformers, electro-magnets for closing said contacts, connections whereby an electro-magnet is momentarily energized by an approaching train, a maintaining circuit for the electro-magnet arranged to be closed when the electro-magnet is energized, a signal, and contacts controlled by the signal for closing a shunt circuit for the transformer around the normally-open contact controlled by said electro-magnet and breaking said maintaining circuit.
75. 10. In combination with an electrically-operated road having both rails conductively continuous for all currents, a transformer connected across the rails, a normally-open contact in series with said transformer, an electro-magnet controlling said contact arranged to be energized by an approaching train, a track relay responsive to current from said transformer, a signal controlled by said relay, and contacts controlled by said signal controlling said electro-magnet.
80. 11. In combination with an electrically-operated road having both rails conductively continuous for all currents, normally open-circuited transformers connected at intervals across the rails, and means controlled by a moving train for closing the circuit of a transformer ahead of the train and opening said circuit when the train reaches said transformer.
85. 12. In combination with an electrically-operated road having both rails conductively continuous for all currents, normally open-circuited transformers connected across the rails at intervals, relays connected across the rails adjacent to said transformers having normally closed connections to the rails, and means controlled by a moving train for closing the circuit of a transformer ahead of the train and opening the circuit of the adjacent relay.
90. 13. In combination with an electrically-operated road having both rails conductively continuous for all currents, normally open-circuited transformers connected across the rails at intervals, relays having normally closed connections to the rails adjacent to said transformers, means controlled by a moving train for closing the circuit of a trans-
95. 100. 110. 120. 125. 130.

- former ahead of the train and opening the circuit of the adjacent relay, and a signal near said transformer controlled by a relay ahead of the transformer.
- 5 14. In combination with an electrically-operated road having both rails conductively-continuous for all currents, normally open-circuited transformers connected at intervals across the rails, means controlled by a moving train for closing the circuit of a transformer ahead of the train, a relay responsive to alternating-current connected to the rails ahead of the transformer, a signal guarding the portion of track between said transformer and relay controlled by said relay, and means for opening the circuit of the transformer when the train enters the portion of track guarded by said signal.
- 10 15. In combination with an electrically-operated road having both rails conductively continuous for all currents, normally open-circuited transformers connected across the rails, means controlled by a moving train for closing the circuit of a transformer ahead of the train, track relays responsive to alternating-current, and signals controlled by said relays adapted to give clear, caution, and danger indications.
- 15 16. In combination with an electrically-operated road having both rails conductively continuous for all currents, normally open-circuited transformers connected across the rails, means controlled by a moving train for closing the circuit of a transformer ahead of the train, track relays responsive to alternating current, each transformer being adapted to energize a plurality of relays, and signals controlled by said relays adapted to give clear, caution and danger indications.
- 20 17. In combination with an electrically-operated road having both rails conductively-continuous for all currents, normally deenergized track relays responsive to alternating current only, and means controlled by a moving train for energizing a track relay 45 ahead of the train.
- 25 18. In combination with an electrically-operated road having both rails conductively-continuous for all currents normally deenergized track relays responsive to alternating current only, means controlled by a moving train for energizing a plurality of relays ahead of the train, and signals controlled by said relays adapted to give clear, caution and danger indications.
- 30 19. In combination with an electrically-operated road, a short insulated section interposed in a rail of the track, a conductor bridging said section to preserve the continuity of the rail for the power-current, a transformer for supplying signal current to the track, normally-open contacts in series with the transformer, and an electro-magnet connected to said insulated section controlling said contacts.
- 35 20. In combination with an electrically-operated road, a short insulated section interposed in a rail of the track, a conductor bridging said section to preserve the continuity of the rail for the power-current, a transformer for supplying signal-current to the track, normally-open contacts in series with the transformer, an electro-magnet connected to said insulated section controlling said contacts, and a maintaining circuit for said magnet arranged to be closed when said magnet is energized.
- 40 In witness whereof, I have hereunto set my hand this 6th day of November, 1906.
